Attorney

UNITED STATES PATENT OFFICE.

WASHINGTON M. POTTER, OF FREEDOM, PENNSYLVANIA.

LUNCH KIT.

1,404,405.

Specification of Letters Patent. Patented Jan. 24, 1922.

Application filed December 4, 1920. Serial No. 428,343.

To all whom it may concern:

Be it known that I, WASHINGTON M. POTTER, a citizen of the United States, residing at Freedom, in the county of Beaver and State of Pennsylvania, have invented certain new and useful Improvements in Lunch Kits, of which the following is a specification, reference being had to the accompanying drawings.

10 This invention relates to certain improvements in lunch kits and primarily it is an object of the invention to provide a novel and improved device of this general character which is an improvement upon the 15 type of lunch kit particularly disclosed in my Patent No. 1,380,019, dated May 31, 1921.

Furthermore, it is an object of the invention to provide a device of this general character embodying novel and improved means 20 whereby the same may be effectively supported in proper position for use as a table.

The invention consists in the details of construction and in the combination and arrangement of the several parts of my improved lunch kit whereby certain important advantages are attained and the device rendered simpler, less expensive and otherwise more convenient and advantageous for use, as will be hereinafter more fully set forth.

30 The novel features of my invention will hereinafter be definitely claimed.

In order that my invention may be the better understood, I will now proceed to describe the same with reference to the accompanying drawings, wherein:

Figure 1 is a vertical sectional view taken through my improved device when employed as a table, the coacting and adjacent portions of an automobile being diagrammatically indicated by dotted lines.

Figure 2 is a vertical sectional view taken longitudinally through my improved device when folded or compacted to be used as a receptacle or container.

45 Figure 3 is a view in bottom plan of the device as illustrated in Figure 2.

Figure 4 is a view in bottom plan of the device as illustrated in Figure 2, with the supporting legs omitted.

50 Figure 5 is a view partly in section and partly in elevation illustrating the supporting legs in extended or working position, with only the bottom panel of the receptacle illustrated.

55 Figure 6 is a fragmentary view in per-

spective illustrating an end portion of the kit in folded arrangement.

As disclosed in the accompanying drawings, 1 denotes a bottom panel or section preferably oblong in form and having hing- 60 edly connected with each longitudinal margin thereof a side wall or panel 3.

4 and 19 denote end members or panels, each removably maintained in applied position when the device is compacted or folded 65 for use as a receptacle or container. Each of the panels 4 and 19 has the bottom and side marginal portions defined by the inwardly disposed flanges 5 which overlie the outer faces of the bottom member or panel 70 1 and the side members or panels 3 when in folded relation. Extending along the upper edge of the end panel 4 or 19 is a strip 8 of a width sufficient, when in one position, to overlie the top panel or member 9. Each 75 end of the strip 8 is provided with an inwardly directed web or flange 10 pivotally engaged, as at 11, with an upper corner or portion of a side member or panel 3 so that the strip 8 may be readily swung to fa- 80 cilitate the removal of the end member or panel 4 or to facilitate the maintenance thereof in applied position.

9 denotes a top panel which snugly fits between the upper marginal portions of the 85 side members or panels 3 and the end members or panels 4 and 19. The top panel 9 is held against removal, when applied, by the strips 16 extending along the outer or upper longitudinal margins of the side members 90 or panels 3, each of said strips being of a width to overlie the adjacent longitudinal marginal portion of the applied top member or panel 9. Each end portion of a strip 16 is provided with an inwardly directed flange 95 17 which is pivotally engaged, as at 18, with an end edge of the side panel 3 so that the strip 16 may be readily swung into either an operative or inoperative position. The strips 8 in the adjacent end portions of the 100 top panel 9 are provided with the coacting locking members 20.

One end portion of the bottom panel 1 is provided with an engaging structure A and which coacts with one or more brackets 31 105 as is particularly described and claimed in my pending application hereinbefore mentioned.

My present invention particularly relates to means for supporting the end portion of 110

the bottom panel 1 remote from the engaging structure A when the device is being used as a table. The longitudinal marginal portions of the bottom panel 1 are defined by the depending flanges or ribs 51 and the under face of said bottom panel adjacent its ends and substantially midway its length is provided with the transversely disposed bracing cleats or members 52, each 10 of a length to terminate a distance inwardly of the flanges or ribs 51 whereby the channels 53 are provided.

Coacting with the end portion of the bottom panel 1 remote from the engaging structure A is a pair of leg sections 54. Each of said leg sections 54 has one end portion pivotally supported, as at 55, within a channel 53 and said leg sections 54 are substantially coextensive in length with the bottom panel 1 so that when said leg sections are compacted with respect to said panel, they will snugly contact with the bottom of the panel 1 and be received in a longitudinally aligned series of channels 53.

25 Pivottally engaged with the outer or free end portion of each of the leg sections 54 is a second leg section 56 which is adapted to be alined with the leg section 54. The leg sections 54 and 56 are maintained in alinement by a sleeve or barrel 57 slidable upon the sections 54 and 56 and which is adapted to be moved into a position as illustrated in Figures 1 and 5 to lock the joint between the sections 54 and 56.

35 The sleeves or barrels 57 coacting with the sets of leg sections 54 and 56 are connected by an interposed web or plate 58 so that the sleeves or barrels 57 will be adjusted or moved in unison.

40 When the leg sections 54 are folded or compacted in close contact with the under surface of the bottom panel 1, the sleeves or barrels 57 are moved inwardly of the leg sections 54 so that the leg sections 56 may be 45 folded upwardly, the end channels 53 remote from the pivotal mounting of the leg sections 54 terminating in notches or recesses 59 to receive said leg sections 56 when upwardly disposed or directed inwardly of the 50 device when compacted or folded to provide a receptacle or container.

It is to be understood that the leg sections 54 and 56 are folded or compacted before the end members or panels 4 and 19 are 55 applied. The members 4 and 19, when applied, serve to hold said folded leg sections 54 and 56 in said folded or compacted condition and particularly through the instrumentality of the flanges 5 and the swing- 60 ing strips 8.

In practice, the engaging means of the bottom panel 1 is applied to the bracket or brackets 31 and preferably after the sets of leg sections 54 and 56 have been locked into 65 alined position. The alined leg sections 54

and 56 are inclined inwardly and downwardly to engage the floor of the automobile or the like, such angle being such as to maintain the bottom panel 1 in desired position. By this particular arrangement of the 70 supporting leg sections 54 and 56 and as is illustrated in Figure 1, it will be at once obvious that provision is made whereby the possibility of the device when mounted for use as a table, being displaced as by contact of the feet with the supporting leg sections is substantially entirely eliminated. 75

From the foregoing description it is thought to be obvious that a lunch kit constructed in accordance with my invention 80 is particularly well adapted for use by reason of the convenience and facility with which it may be assembled and operated, and it will also be obvious that my invention is susceptible of some change and modification 85 without departing from the principles and spirit thereof and for this reason I do not wish to be understood as limiting myself to the precise arrangement and formation of the several parts herein shown in carrying 90 out my invention in practice except as hereinafter claimed.

I claim:

1. A lunch kit comprising a bottom panel, side panels hingedly connected thereto, removable end panels, a top panel, a supporting leg section pivotally engaged with one end portion of the bottom panel and substantially of a length coextensive with the length of the bottom panel, and a second leg 100 section pivotally engaged with the outer end portion of the first leg section and foldable inwardly of the kit when compacted, with the first leg section closely adjacent to the bottom panel, an end panel holding said leg 105 sections in their folded relation.

2. A lunch kit comprising a bottom panel, side panels hingedly connected thereto, removable end panels, a top panel, a supporting leg section pivotally engaged with one end portion of the bottom panel and substantially of a length coextensive with the length of the bottom panel, a second leg 110 section pivotally engaged with the outer end portion of the first leg section and foldable 115 inwardly of the kit when compacted, with the first leg section closely adjacent to the bottom panel, an end panel holding said leg sections in their folded relation, and means coacting with the leg sections for holding the 120 same substantially alined when extended.

3. A lunch kit comprising a bottom panel, side panels hingedly connected thereto, removable end panels, a top panel, a supporting leg section pivotally engaged with one 125 end portion of the bottom panel and substantially of a length coextensive with the length of the bottom panel, a second leg section pivotally engaged with the outer end portion of the first leg section and foldable inwardly 130

of the kit when compacted, with the first leg section closely adjacent to the bottom panel, an end panel holding said leg sections in their folded relation, and a sleeve slidably 5 along the leg sections for locking the same, when in one position, substantially in alignment.

4. A lunch kit comprising a bottom panel, side panels hingedly connected thereto, 10 movable end panels, a top panel, a supporting leg section pivotally engaged with one end portion of the bottom panel and substantially of a length coextensive with the length of the bottom panel, and a second leg 15 section pivotally engaged with the outer end portion of the first leg section and foldable inwardly of the kit when compacted, with the first leg section closely adjacent to the bottom panel, an end panel holding said leg 20 sections in their folded relation, a face of

the bottom panel being provided with channels to receive the first named leg section when moved immediately adjacent the bottom panel.

5. A lunch kit comprising a bottom panel, 25 side panels hingedly connected thereto, end panels, one of said end panels being removable, a supporting leg section hingedly connected with an end portion of the bottom panel and of a length substantially coextensive 30 with the length of the bottom panel, and a second leg section pivotally engaged with the outer end portion of the first named leg section and foldable inwardly of the kit when compacted, said removable end panel, 35 when applied, holding the leg sections in folded relation.

In testimony whereof I hereunto affix my signature.

WASHINGTON M. POTTER.
